UNITED STATES PATENT OFFICE.

THEODOR KOZLOWSKY AND WOJCIECH ROGOSKY, OF TOLEDO, OHIO.

COMBINED BRUSH AND COMB.

1,388,955.

Specification of Letters Patent. Patented Aug. 30, 1921.

Application filed March 24, 1921. Serial No. 455,055.

To all whom it may concern:

Be it known that we, THEODOR KOZLOWSKY and WOJCIECH ROGOSKY, citizens of Poland, residing at Toledo, in the county of Lucas and State of Ohio, have invented certain new and useful Improvements in Combined Brushes and Combs, of which the following is a specification.

This invention relates to hair dressing articles generally, having particular reference to a device in which a comb and brush are combined in a single unitary structure.

The invention has for an object to provide a novel means for mounting a comb and brush in a single structure whereby the comb and brush can be more readily alternated in use.

A further object is to provide a device in which the comb may be carried within the brush backing when not in use and have its teeth readily projected from the latter for use, and also to provide for the automatic cleaning of the teeth of the comb as the same is withdrawn into the brush back.

For further comprehension of the invention, and of the objects and advantages thereof, reference will be had to the following description and accompanying drawings, and to the appended claims in which the various novel features of the invention are more particularly set forth.

Figure 1 of the drawings is a rear view of a device embodying the invention.

Fig. 2 is a similar view with the back plate removed.

Fig. 3 is a transverse section on the line 3-3 of Fig. 1.

As here shown our improved device comprises a brush element consisting of a back 40 having a handle extension 11 and provided with the usual bristles 12. The handle 11 may have a mirror 11' mounted thereon. Within the back 10, on the rear side thereof, is formed a recess 13, which extends the major 45 portion of the area of the back and is covered by a plate 14 secured in place by screws 15.

This recess is adapted to accommodate a comb 16, which is in the main of ordinary construction, and is adapted to project from 50 one side of the recess 13. Formed on opposite ends of this comb, at the back edge thereof, are a pair of lugs 17, which project transversely into a pair of transverse grooves 18 in the bottom wall of the recess 13 and serve 55 as guides to prevent angular displacement of the comb.

The comb 16 is held in the projected position shown, by an abutment element comprising a segmental arm 20 fulcrumed as at 21' on a suitable stud in the brush back 10 and 60 having a series of fingers 21, 22, 23 of different radial lengths, these fingers being adapted to be engaged in a notch 24 in the back of the comb 16, this notch 24 and the fulcrum point 21 of the arm having a relative 65 position in the line of movement of the comb so as to prevent any turning moment on the arm 20 due to back thrust of the comb. The arm 20 may have a handle extension 25 which projects from the recess 13 oppositely 70 to the comb 16.

The comb 16 is moved back into the recess 13 when the arm 20 is swung to one side by the handle 25, by a pair of coiled expansion springs 27 seated in the grooves 18 and bearing on the lugs 17. Inward movement of the comb 16 under the influence of the springs 27 may be limited by a pair of shoulders 10' formed on the brush back 10.

The teeth of the comb 16 project between a 80 series of projections 30 extending along the side of the recess 13, these projections having a snug fit with the teeth, and having sharp outer corners which, by rubbing along the teeth, act to clean the latter as the comb 85 moves into the recess 13.

It is believed that the manner of operation of our improved device will be readily understood from the foregoing description. Normally the comb is concealed in the brush 90 back while only the tip of handle 25 projects. When the handle is swung to one side the fingers 21, 22, 23 act on the back of the comb with a cam action and move it to the projected position. Either of these fingers may 95 be engaged in the notch 24 according to the distance it may be desired to project the teeth of the comb.

Having thus described our invention what we claim as new and desire to protect by Letters Patent of the United States is as follows:—

1. A device of the class described comprising a brush including a back having a recess therein, a comb slidable in said recess, a 105 spring normally urging said comb into said recess, and means locking said comb in position with its teeth projected from said recess, said means including an abutment arm pivoted to said back and adapted to be engaged 110 by the rear edge of the comb.

2. A device of the class described compris-

ing a brush including a back having a recess therein, a comb slidable in said recess, a spring normally urging said comb into said recess, and means locking said comb in position with its teeth projected from said recess, said means including an abutment arm pivoted to said back, and having a series of circumferentially spaced abutment fingers of different radial lengths any one of which is 10 adapted to be brought into operative engagement with the rear edge of the comb, for the purpose specified.

3. A device of the class described comprising a brush including a back having a recess 15 therein, a comb slidable in said recess, lugs on said comb engaging grooves in the bottom wall of said recess to guide said comb, and means on said back engaging the teeth of the 20 comb and acting both to clean said teeth during inward movement of the comb, and to co-operate with said lugs in guiding the comb.

4. A device of the class described comprising a brush including a back having a recess therein, a comb slidable in said recess, lugs 25 on said comb engaging grooves in the bottom wall of said recess to guide said comb, and means on said back engaging the teeth of the comb and acting both to clean said teeth during 30 inward movement of the comb, and to co-operate with said lugs in guiding the comb, a pair of springs located in said grooves and engaging said lugs to urge the comb into said

recess, and a variable abutment to hold said comb with its teeth projected from said recess.

35

5. A device of the class described comprising a brush including a back having a recess therein, a comb slidable in said recess, lugs on said comb engaging grooves in the bottom wall of said recess to guide said comb, coiled 40 expansion springs located in said grooves and engaging said lugs to urge the comb into the said recess, and means locking said comb in position with its teeth projected from said recess.

45

6. A device of the class described comprising a brush including a back having a recess therein, a comb slidable in said recess, lugs on said comb engaging grooves in the bottom wall of said recess to guide said comb, coiled expansion springs located in said grooves and engaging said lugs to urge the comb into the said recess, and means locking said comb in position with its teeth projected from said recess, said means comprising an abutment 50 arm pivoted to said back, a series of circumferentially spaced abutment fingers of different radial lengths on said arm, and a handle extension on said arm projecting edgewise of the brush back from the said recess.

55

In testimony whereof we have affixed our signatures.

THEODOR KOZLOWSKY.
WOJCIECH ROGOSKY.
